UNITED STATES PATENT OFFICE.

JOHN J. MCINTYRE, OF INVERNESS, NOVA SCOTIA, CANADA, ASSIGNOR OF ONE-HALF
TO JOHN MCFARLANE, OF INVERNESS, NOVA SCOTIA, CANADA.

VALVE.

1,247,696.

Specification of Letters Patent. Patented Nov. 27, 1917.

Application filed June 18, 1915, Serial No. 34,903. Renewed July 25, 1917. Serial No. 182,800.

To all whom it may concern:

Be it known that I, JOHN J. MCINTYRE, a subject of the King of England, residing at Inverness, in the Province of Nova Scotia 5 and Dominion of Canada, have invented certain new and useful Improvements in Valves, of which the following is a specification, reference being had therein to the accompanying drawing.

10 This invention relates to linings for valves and construction of valves and the like wherein the linings and working portions of the valves are formed of wood, especially treated for use in connection with pumps 15 and the like.

Another object of this invention is the production of a simple and efficient means whereby the staves forming the lining for the valve will be firmly clamped against the 20 inner walls of the valve without the necessity of employing means other than the working portions of the valve itself.

With these and other objects in view, this 25 invention consists of certain novel combinations, constructions, and arrangements of parts as will be hereinafter fully described and claimed.

In the accompanying drawing:—

Figure 1 is a vertical section through the 30 valve.

Fig. 2 is a top plan view of the cover of the valve.

Fig. 3 is a side elevation, partly in section, of the valve seat.

35 Referring to the accompanying drawing by numerals it will be seen that 1 designates the outer portions of the valve casing which is provided with an inner cone-shaped pocket 2. The casing 1 is provided with an aperture 3 extending through the bottom thereof in which is placed a wooden valve seat 4 especially treated to resist chemical action. The valve seat 4 is provided with an annular flange 5 upon the bottom end 40 thereof upon which is placed a metallic extension band 6 for reinforcing the valve seat and preventing the same from splitting. An annular flange 7 is formed upon the casing 1 and a plurality of bolts 8 extend 45 through this flange 7 for firmly anchoring the casing 1 in engagement with the support 9.

50 The casing 1 is provided with a plurality of laterally extending ears 10 between which

are pivotally mounted the cover engaging 55 bolts 11 upon which nuts 12 are fitted. The bolts 11 fit in the notched portions 13 formed in the cover 14 for firmly locking or clamping the cover 14 in engagement with the casing 1. A plurality of substantially inverted U-shaped handles 15 are secured to the cover or top 14 for permitting the top or cover 14 to be easily and conveniently handled and removed from the casing 1 when so desired. 65

The cap 16 is seated upon the top of the casing 1 and is provided with a reduced extension 17, which extension is provided with a centrally located aperture 18 having a lining 19. The valve 20 is seated upon 70 the valve seat 4 and is provided with a tapering lower end 21 for facilitating the seating of the valve 20 within the aperture 22 formed in the valve seat 4. The valve 20 is provided with a reduced neck extension 23 working in the aperture 18, which aperture constitutes a guide for the valve 20. 75

The casing 1 is provided with a ledge portion 24 upon which ledge portion is placed a plurality of closely fitting wooden 80 staves 25, the inner ends of which engage the outer face of the valve seat 4 and the outer ends engage the inner faces of the side staves 26. These side staves 26 are placed against the inner face of the casing 85 1 and it will therefore be seen that the bottom staves 25 will be firmly wedged between the inner faces of the staves 26 and the outer face of the valve seat 4.

The upper ends of the staves 26 will be 90 clamped against the side walls of the casing 1 by means of the outer wall of the cap 16, as shown in Fig. 1 of the drawing.

From the foregoing description it will 95 be seen that a very simple and efficient lining and valve construction has been produced for use where wooden parts are employed for firmly holding the several parts in an assembled relation and presenting a minimum amount of wear thereon. 100

What I claim is:—

A device of the class described comprising a valve casing, said valve casing provided with a valve seat extending up through a portion of said casing, said valve casing provided with a ledge portion adjacent said valve seat, a plurality of wooden staves fitted upon said ledge portion and abutting 105

against the outer face of said valve seat, said casing provided with a cone-shaped inner portion, a plurality of staves engaging the inner face of said casing and fitting between the inner walls of said casing and the outer face of said first-mentioned staves, whereby said first-mentioned staves will be

firmly held in a wedge-like position upon said ledge portion, a valve mounted upon said valve seat, and means for retaining said valve within said casing.

In testimony whereof I hereunto affix my signature.

JOHN J. McINTYRE.
